ICANDOIT Exfoliation Set-17.71 Inch Boar Bristles Back Scrubber, posted Sep. 6, 2024 [online], [retrieved Jul. 1, 2025]. Retrieved from internet, <https://www.amazon.com/dp/B0DG99YVNJ/?th=1> (Year: 2024).*Primary Examiner — Lauren D Mcvey*Assistant Examiner* — Evin F Ershock(74) Attorney, Agent, or Firm — All West Law Group PLLC; Aaron Powell(57) CLAIM

The ornamental design for a back scrubber brush for shower as shown and described.

DESCRIPTION

FIG. 1 is a perspective view of a back scrubber brush for shower showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof; and,

FIG. 9 is a partial enlarged view of portion 9 in FIG. 1. The broken lines depict portions of the back scrubber brush for shower and form no part of the claimed design.

The dot dash line is included for the purpose of illustrating the bounds of the enlarged view and forms no part of the claimed design.

1 Claim, 9 Drawing Sheets(56)
